(57) **CLAIM**

The ornamental design for a hose pot, as shown and described.

DESCRIPTION

FIG. 1 is a top front perspective view of the hose pot of the present invention;

FIG. 2 is a left side view thereof;

FIG. 3 is a front view thereof;

FIG. 4 is a right side view thereof;

FIG. 5 is a rear view thereof; and,

FIG. 6 is a bottom rear perspective view thereof.

The portions of the hose pot illustrated in broken lines form no part of the claimed hose pot design.
